US0D1088922S

(12) **United States Design Patent** (10) **Patent No.:** **US D1,088,922 S**
(45) **Date of Patent:** **** Aug. 19, 2025**

(54) **CAR OBD CODE READER SCANNER**

(71) Applicant: **Yundong Xuan**, Zhejiang (CN)

(72) Inventor: **Yundong Xuan**, Zhejiang (CN)

(**) Term: **15 Years**

(21) Appl. No.: **29/908,591**

(22) Filed: **Jan. 12, 2024**

(51) **LOC (15) Cl.** **10-05**

(52) **U.S. Cl.**

USPC **D10/78**

(57) **CLAIM**

The ornamental design for a car OBD code reader scanner as shown and described.

DESCRIPTION

FIG. 1 is a perspective view of a car OBD code reader scanner showing my new design;

FIG. 2 is another perspective view thereof;

FIG. 3 is a front view thereof;

FIG. 4 is a back view thereof;

FIG. 5 is a left view thereof;

FIG. 6 is a right view thereof;

FIG. 7 is a top plan view thereof;

FIG. 8 is bottom plan view thereof;

FIG. 9 is a partial enlarged view of portion 9 in FIG. 1; and, FIG. 10 is a partial enlarged view of portion 10 in FIG. 2. The broken lines depict portions of the car OBD code reader scanner and form no part of the claimed design.

1 Claim, 10 Drawing Sheets
